WICK-FEEDING MEANS FOR APPLICATORS
OF COSMETICS AND THE LIKE

Dezelle Ostrander, South San Francisco, Calif.

Application June 24, 1946, Serial No. 678,769

1 Claim. (Cl. 15—134)

1
This invention relates to applicators and is especially adapted to provide a sanitary and convenient means of applying various medicinal or cosmetic liquids, salves, pastes, etc. to skin surfaces.

An important object of the invention is to provide an applicator of this character which employs a wick which is previously impregnated with the substance to be used or wherein the wick absorbs the substance by capillary attraction, especially when the substance is in a liquid state.

Another important object of the invention is to provide an applicator for substances, as named, wherein an applying wick is employed, that may be advanced and cut off conveniently.

Still another object of the invention is to provide an applicator for the purposes stated, wherein a wick is provided for supplying the desired substance from a container or reservoir, and wherein convenient complementary cutting means is provided whereby the used end of the wick can be cut off from time to time, especially when the applicator is to be used by different persons.

These and various other important objects and advantages of the invention, will become apparent to the reader of the following description.

In the drawing:

Figure 1 is a longitudinal sectional view through the applicator;

Figure 2 is an enlarged fragmentary sectional view taken on line 2—2 of Figure 1 or Figure 2;

Figure 3 is a reduced side elevational view of the device;

Figure 4 is a cross section taken on line 4—4 of Figure 1.

Referring to the drawing, numeral 5 denotes a substantially bullet-shaped shell, the same having a cylindrical portion *a* and a gradually constricted nose portion *b*.

The reduced end of the shell 5 is cut off bluntly as at 6 and has an opening 7 therethrough for receiving the plug portion 8 of a cap 9 which may have a ring 10, and to also slidably receive a tube 11 which forms part of the internal mechanism of the applicator.

An elongated reservoir 12 contains a substance 13, which may be a medicinal or cosmetic liquid, salve, paste, etc. and into this extends a wick, preferably of felt and denoted by numeral 14. The wick extends through the tube 11 and partly projects beyond the free end thereof, as shown in Figure 2.

The reservoir 12 has a slight taper inwardly, so that there will be a frictional engagement of

2
the outer end thereof with the adjacent interior of the shell 5.
The reduced end of the reservoir 12 has a threaded opening 15 for receiving the adjacent threaded end of the tube 11. Radiating from this end of the tube 11 is a flange 16, fixed to the tube and from this point, longitudinally of the tube 11, the latter is formed with a slot 17, into which a feed spur 18, formed from a second flange 19, located on a collar 20 projects. The collar 20 with its flange 19 is slidable on the tube 11. A coiled compression spring 21, circumscribes the tube 11 and is interposed between the flanges 16, 19. The feed spur 18 projects at an angle into the tube 11 so as to barely bite into the wick 14.

The lower end of the reservoir 12 has a hemispherical-shaped head 22, the central portion of which has a recess 23 for receiving the plug and cap 8, 9 when the applicator is being used.

In the use and operation of the applicator, the cap 9 is first removed from the applying end of the device and the plug 8 thereof inserted in the recess 23 of the reservoir head 22, so that it will not become lost. By pushing inwardly on the head 22, the reservoir 12 is urged inwardly until the flange 19 abuts the reduced end of the shell 5. The parts will thus assume the position shown in Figure 2, with a short portion of the wick 14 protruding, and this is used for applying cosmetics, medicinals and other substances.

If it is desired to remove the tip of the wick, as when another person is about to use the same, the tip can be cut off by means of a cutter generally referred to by numeral 24. This cutter is a sleeve which snugly fits the cylindrical portion of the shell 5 and has a diamond-shaped opening 25 therein, the edge portions of the sleeve at said opening 25 being sharpened to provide cutting edges 26. This sleeve is slipped off of the shell 5 and laid across the blunt end 6 of the shell 5 with the tip of the wick protruding through the opening 25. By pulling the cutter across the blunt end 6, the tip is cut off.

It will now be necessary to extend the wick for use, and this is accomplished by forcing the reservoir 12 inwardly so that the tube 11 is projected a short distance beyond the blunt end 6 of the shell 5, that is until the spring 21 is fully compressed, or the flange 16 has touched the adjacent end of the collar 20. During this movement of the tube 11, the wick 14 has been carried over the slightly impinging feed spur 18, but upon release of the reservoir 12, the spring

21 will exert force on the reservoir, urging the same outwardly, and in so doing, the wick 14 will be caught against the feed spur 18 and retained as the tube 11 moves inwardly with the reservoir. Thus, when the parts have returned to the position shown in Figure 2, or to the position shown in Figure 1, a portion of the wick will be protruding beyond the free end of the tube 11.

Obviously, the various parts of the device can be manufactured of any desired material, and perhaps plastic or some material yet to be discovered will be found suitable.

It will also be found obvious that there is no waste of the substance being applied, whether it be a medicinal or a cosmetic. The application is done from a wick, impregnated and a thorough brushing action of the material onto the skin can be accomplished by the small protecting tip portion of the wick.

While the foregoing description sets forth the invention in specific terms, it is to be understood that numerous changes in the shape, size and materials may be resorted to without departing from the spirit and scope of the invention as claimed hereinafter.

Having described the invention, what is claimed as new is:

An applicator comprising a shell, a substance containing reservoir disposed slidably through one end of the shell, the other end of the shell being formed with an opening, said cartridge being provided with a sleeve extension disposed in the last mentioned opening, a flanged collar on the sleeve adjacent the reservoir, a second flanged collar through which the sleeve is slid-

5 able and bearing against the inside of the shell at the last mentioned end thereof, a compression spring interposed between the flanged collars and impinging against the same, a wick extending from within the reservoir and through the sleeve, said wick having frictional engagement with said sleeve, said sleeve being formed with a longitudinal slot, the last mentioned flanged collar being provided with a tooth projecting inwardly through the slot of the sleeve and at an acute angle to the longitudinal axis of that portion of the wick extending inwardly into the cartridge to bite into the wick, said tooth being adapted to retain the wick against return, with respect to the shell on the inward movement of the reservoir with respect to the shell and outwardly of the reservoir, on the outward movement of the cartridge with respect to the shell.
